BREAD TRAY

William C. P. Zabel and Richard C. Helfenbein,
Chicago, Ill., assignors to Plasmetl Corporation,
Chicago, Ill., a corporation of Illinois

Application January 2, 1948, Serial No. 143,496

Term of patent 14 years

(Cl. D44—10)

To all whom it may concern:

Be it known that we, William C. P. Zabel and Richard C. Helfenbein, both citizens of the United States, and both residents of Chicago, in the county of Cook and State of Illinois, have invented a new, original, and ornamental Design for a Bread Tray, of which the following is a specification, reference being had to the accompanying drawing, forming a part thereof, and in which:

Fig. 1 is a top plan view of a bread tray, showing our new design;

Fig. 2 is a bottom plan view;

Fig. 3 is a side elevational view; and

Fig. 4 is a fragmentary sectional view of the same taken along line 4—4 of Fig. 1.

We claim:

The ornamental design for a bread tray, as shown.

WILLIAM C. P. ZABEL.
RICHARD C. HELFENBEIN.
